UNITED STATES PATENT OFFICE.

JOHN J. FITZGIBBON AND JOHN M. TRAVIS, OF ST. LOUIS, MISSOURI.

FAUCET.

No. 831,049.

Specification of Letters Patent.

Patented Sept. 18, 1906.

Application filed April 8, 1905. Serial No. 264,553.

To all whom it may concern:

Be it known that we, JOHN J. FITZGIBBON and JOHN M. TRAVIS, citizens of the United States, residing at St. Louis, State of Missouri, have invented certain new and useful Improvements in Faucets, of which the following is a full, clear, and exact description, reference being had to the accompanying drawings, forming a part hereof.

10 Our invention has relation to improvements in faucets for carbonated beverages; and it consists in the novel construction and arrangement of parts more fully set forth in the specification, and pointed out in the 15 claims.

In the drawings, Figure 1 is a combined section and front elevation of our improved faucet, showing the valves in normal position. Fig. 2 is a top plan of the invention. Fig. 3 20 is a vertical transverse section on line 3 3 of Fig. 2. Fig. 4 is a section similar to Fig. 1, showing, however, one of the syrup-valves and water-valve in their depressed position. Fig. 5 is a vertical transverse section on line 25 5 5 of Fig. 2, and Fig. 6 is an inverted perspective of the operating lever or handle.

The present invention is an improvement on the construction of faucet shown and described in United States Letters Patent No. 30 785,869, issued to us under date of March 28, 1905, and has for its object the simplification of the patented device in particulars directed to the disposition of the passages for conducting the syrup and carbonated water and 35 to the means for actuating the valves by which these passages are controlled.

A further object is to impart an additional function to the operating lever or handle, whereby the latter may control either both 40 the syrup and water valves or the water-valve alone, depending on the particular initial movement imparted to said lever by the operator.

In detail the invention may be described 45 as follows:

Referring to the drawings, C represents a suitable casting or body portion, the same being provided with a series (two in the present case) of syrup receptacles or basins 1 1 to 50 receive syrups of different flavor, said receptacles being disposed at each end of the casting, as shown. The top of each receptacle is closed by a screw-cap 2, provided with air-vents 3, the lower edge of the screw-threaded rim thereof bearing against the 55 edge of a yielding rubber diaphragm 4, sus-

pended in the receptacle from the annular ledge or shoulder 5, between which and the edge of the screw-cap rim said diaphragm is held. The lower end of each syrup-receptacle has leading therefrom a passage 6, which communicates with a vertical passage 7, passing entirely through the body portion of the faucet.

Leading rearwardly from the passage 7, at 65 a point about midway of the length thereof, is a passage 8, which connects to the syrup-supply pipe 9, leading to any source of syrup-supply. (Not shown.)

Operating in the passage 7 and normally 70 projecting a slight distance above the upper surface of the body of the casting C is a reciprocating valve 10, provided with an intermediate reduced stem 10' and a terminal basal head 10'', said head operating in a correspondingly-enlarged extension of the passage 7 and in a pocket 11 of the casting, forming a part of the delivery spout or nozzle 12. Within this pocket and below the head 10'' is confined a spring 13, which forces 75 the valve to its normal position referred to, its upward travel being limited by the shoulder 14, intercepting the head below the passage 6. With the valve 10 in its normal position the passage 8 is in free communication 80 with the passage 7 and the latter with passage 6, so that the syrup is free to flow into the receptacle 1. In filling the receptacle the syrup gradually lifts or displaces the diaphragm 4 until it drives it to the dotted position shown in Fig. 1, the air above the diaphragm escaping through the vents 3. Of 85 course in the emptying of the receptacle, as presently to appear, the diaphragm resumes the depressed position shown in Fig. 1. The 90 diaphragm not only insures the dispensing of uniform quantities of syrup, since it limits the quantity flowing into the receptacle, but prevents the overflowing of the receptacle at any time.

Leading from the enlarged extension of the passage 7, in which the head 10'' operates, and located relatively below the passage 6, is a passage 15, which leads to the bottom of the water-discharge passage 16, the upper 105 end of the latter communicating with the rearwardly-extending horizontal feed-passage 17 and the lower end communicating with the passage of the discharge-nozzle 12. The rear end of the passage 17 communicates 110 with the rear vertical passage 18, which in turn (at a point below the passage 17) com-

municates with the carbonated-water-supply pipe 19, leading to any source of supply. (Not shown.) The passage 18 also extends the full height of the casting, being controlled by a reciprocating valve 20, similar to valves 10 10. The valve 20 is provided with a disk 21, bounded on either side by the reduced portions or stems 22 23, the latter terminating in a head or socket 24, receiving one end 10 of the coiled spring 25, confined in the pocket 26 of the casting of which the discharge-nozzle forms a part. The disk 21 controls the flow of the carbonated water from the pipe 19 to the passage 17, permitting the water to 15 flow freely into said passage upon depression of the valve 20. (See dotted position of the valve in Fig. 5, which brings the disk 21 below the discharge-opening of the pipe 19.)

As in our patented construction above referred to, the valves 10 10 and 20 are actuated by the sweep of the lever or handle 27 in the proper direction. This lever is connected to a rotatable stem or post 28, received in a socket 29 of the casting and held in position 25 by a screw 30, whose inner end engages an annular groove formed about a reduced neck 31 of the post. The upper end of the latter passes through the inclined opening of a hollow boss 32 of the lever, a pin 33 being passed 30 transversely through the boss and post, Fig. 5. On the under surface of the short arm of the lever are disposed two pairs of cam formations 34 35, one cam on each side of the longitudinal axis of the lever, the members of the outer pair of cams serving to ride over the rounded upper end of the valve 20 and the members of the inner pair riding over the rounded upper ends of the valves 10 10, the engagement of the particular member of course 35 depending on the direction in which the lever 40 is swung horizontally. The cams are so formed that whatever be the direction in which the lever is swung one of the syrup-controlling valves 10 and the water-valve 20 45 are depressed simultaneously, allowing the syrup from the proper receptacle to drain into the discharge-nozzle, Fig. 4, there to become intimately mixed with the discharging carbonated water issuing from the pipe 19, 50 passages 17 and 16, and discharge-nozzle 12, respectively. Of course when the valves 10 55 are depressed for the purpose just set forth the passages 8 are closed to cut off the syrup from the main source of supply.

55 By virtue of the inclined passage of the boss 32 and the pin connection 33 the lever or handle 27 is susceptible of an independent movement in a vertical plane—that is to say, it is capable of rocking vertically about the 60 pin 33. This rocking movement enables the rear end of the lever to be depressed sufficiently to depress the valve 20 far enough to allow the carbonated water to escape into the discharge-nozzle without disturbing the 65 syrup-controlling valves 10 10. This move-

ment of the lever, (see dotted position in Fig. 5,) is resorted to when it is desirable to draw off only carbonated water without the syrup—an occasion which often arises, as many persons prefer the water alone to a mixture of 70 syrup and water. In other respects the action of the valves 10 10 and 20 is the same as that of our patented construction above referred to. The several supply-pipes are 75 preferably passed through a shield or fitting 36 in the back of the casting.

We may of course depart in a measure from the details here shown without affecting the nature or spirit of our invention.

Having described our invention, what we 80 claim is—

1. A faucet comprising a body portion having a suitable receptacle, a discharge-nozzle, a discharge-passage leading from the receptacle to said discharge-nozzle, feed-passages 85 communicating with the receptacle and with the discharge-nozzle respectively, valves controlling said feed-passages, and an operating-lever adapted to actuate the respective valves by a movement in one direction, and 90 one of the valves only by a movement in a different direction, substantially as set forth.

2. A faucet comprising a body portion having suitable receptacles, discharge-passages leading therefrom to a common discharge-nozzle, feed-passages communicating with the receptacles and with the discharge-nozzle respectively, valves controlling said passages, and an operating-lever capable of movement in distinct planes and adapted to 100 actuate the series of valves by movements in one plane, and a portion of the valves by an independent movement in a different plane, substantially as set forth.

3. A faucet comprising a body portion having suitable syrup-receptacles, discharge-passages leading therefrom to a common discharge-nozzle, valves controlling the several passages, feed-passages leading to a source of syrup-supply and communicating with the receptacles, a feed-passage leading to a source of carbonated-water supply and communicating with said discharge-nozzle, valves controlling the several passages, and means under the control of the operator for actuating a portion of the series of valves to permit discharge of the liquid and water controlled by them, jointly into the discharge-nozzle, or for actuating only the valve controlling the water-supply, substantially as set forth. 105

4. A faucet comprising a body portion having suitable syrup-receptacles, discharge-passages leading therefrom to a common discharge-nozzle, feed-passages leading to a source of syrup-supply and communicating with the receptacles, a feed-passage leading to a source of carbonated-water supply and communicating with said discharge-nozzle, controlling valves for the several passages, an operating-lever pivoted in proximity to the 110 115 120 125 130

valves and oscillating in distinct planes relatively thereto, and suitable formations on the lever adapted to engage and actuate both the syrup-controlling and carbonated-water-controlling valves for an oscillation of the lever in one plane, and the carbonated-water-controlling valve only, for an oscillation in a different plane, substantially as set forth.

5. A faucet comprising a body portion having suitable syrup - receptacles, discharge-passages leading therefrom to a common discharge-nozzle, means for connecting the latter with a source of carbonated-water supply, feed-passages leading from the receptacles to suitable sources of syrup-supply, a horizontally-swinging lever having an independent movement in a vertical plane, vertically-reciprocating valves controlling the admission of syrup and water from their respective sources of supply, and formations on the lever for actuating the controlling-valves with the swinging of the lever in proper direction, the said lever being adapted to actuate the water-dispensing valve alone by an independent movement in a vertical plane, substantially as set forth.

25 6. A faucet having syrup and carbonated-water-discharge passages leading to a com-

mon discharge-nozzle, valves controlling the admission of syrups and water to said passages, and an operating-handle capable of movement in distinct planes, adapted to actuate one or another portion of the valves according to the plane of movement imparted thereto, substantially as set forth.

7. A faucet comprising a body portion chambered for the passage of syrup and water from suitable sources of supply, a discharge-nozzle, discharge-passages leading from the chambered portions to said discharge-nozzle, feed-passages communicating with the chambered portions and with the discharge-nozzle respectively, valves controlling said feed-passages, and an operating-lever adapted to actuate the respective valves by a movement in one direction, and one of the valves only by a movement in a different direction, substantially as set forth.

35 In testimony whereof we affix our signatures in presence of two witnesses.
